UNITED STATES PATENT OFFICE.

JOHN B. HOUSTON, OF VANCOUVER, CANADA, ASSIGNOR TO WILLIAM H. ARMSTRONG AND ALEXANDER MORRISON, OF SAME PLACE.

RETORT-DOOR AND MEANS FOR CLOSING SAME.

SPECIFICATION forming part of Letters Patent No. 638,122, dated November 28, 1899.

Application filed August 12, 1899. Serial No. 727,019. (No model.)

To all whom it may concern:

Be it known that I, JOHN BROADFOOT HOUSTON, a citizen of the Dominion of Canada, residing at Vancouver, in the Province of British Columbia, Canada, have invented certain new and useful Improvements in Retort-Doors and Means for Closing the Same, of which the following is a specification.

This invention relates to improvements in closure-doors for closing retorts, steam-boxes, or reservoirs adapted to hold steam under high pressure—as, for example, retorts in machines for bending wood—in which I so arrange the door on the pressure side of its seat that the internal pressure will force it forward upon its seat and effectively close the opening.

The object of my invention is to provide a door or closure for a retort or other like vessel that is comparatively cheap to make, light and simple of operation, and one that is effective in its operation by reason of the covers of the openings for the door and its slide-way at the top being sealed by internal pressure. Other advantages over other doors of this class now in use will be seen when this specification and the appended claims are fully understood. I attain this object by the mechanism illustrated in the accompanying drawings, in which—

Figure 1 shows a side view of the retort with a vertical cross-section through the center of the door. Fig. 2 is a front elevation of the door. Fig. 3 is an enlarged detail of one of the fulcra or trunnions on which the flap-door swings that closes the opening through which the door proper passes when being opened. This view is taken on the line *a a* in Fig. 4 in the direction of the arrow. Fig. 4 is the same mechanism taken on the line *b b* in Fig. 3 in the direction of the arrow, and Fig. 5 shows an enlarged detail of the hand-levers for drawing the door forward to its seat before the pressure is turned on.

Similar numerals and letters refer to similar parts throughout all the views.

The vessel A, intended to be closed by my door, as shown in the illustration, is preferably of cylindrical form and is dished at its closed end, as B, so as to give a maximum of strength with a minimum of weight.

10 indicates a stout cast-iron frame secured to the open end of the vessel to be closed. This frame 10 comprises important features of my invention, and as it is required to receive the entire strain of the thrust of the door from within and also provide a means for allowing the door to be raised and lowered through an opening in its top it is essential that this part should be designed on scientific principles.

Directly in front of the lip or rim 10^a, that embraces the open mouth of the vessel A, is an enlarged recess *a*, in which the door 11 is received, this at the bottom being of semicircular form, as better shown in Fig. 2, and passing upward it extends through a raised portion of the frame 10, as 10^b. Arranged in the recess *a* or around in front of the mouth of the retort or vessel A on the frame 10 is an annular rim 10^c. In the center of this rim 10^c is a groove 10^d and fixed in this groove on an even plane is a rubber packing 10^e.

The door 11 is made of the same material as the body of the retort A and is of concavo-convexo form dished outward, the same as the closed end B, and the rim or edge, as 11^a, is bent round, forming a circular rim which when the door is closed fits against the packing 10^e, lying in the groove 10^d.

For drawing the door to its seat 10^e before the pressure is turned on I provide hand-levers 12, pivotally fulcrumed on pins or studs 13 on the inner opposite edges of the rim 10^c. These hand-levers 12 are provided with projections 14 on their outer sides between their points of pivot and their inner ends, and as these levers are moved upward the projections 14 will engage fixed brackets 15 on the opposite sides of the door 11 and pull it forward against its seat, and as the said levers are reversed - pressed downward the inner ends will engage the door 11 in the annular hollow (see Fig. 1) formed by the dish and the rim 10^c and press it back from the rubber seat, so that the seat will not be dragged in the operation of raising the door.

Securely fixed to the lower outer side of the door is a bracket 16, and rigidly bolted to this is a horizontal bar 17, the opposite ends of which are rounded off and provided with small antifriction-rollers 18.

Fulcrumed on studs 19, projecting from the opposite exterior sides of the vessel A, are balance-levers 20, the forward ends of which are slotted, as 20^a, which slots receive the 5 rollers 18 and allow them to move to the versed sine of the arc as the door 11 is moved up and down. On the opposite ends of the levers 20 are balance-weights 21, which may be adjusted by moving to make the door properly 10 balance.

For closing the upper side of the opening a at the top of the frame 10, through which the door 11 is passed when raised, I provide a flap-door 22, which is preferably made of 15 the same material as the door 11 and is dished downward to make it rigid. The engaging edge of this flap-door is on an even plane and when closed is received on a packing-strip 23, fixed in a groove 10^c around the said opening. Securely fixed near the opposite ends of this flap-door 22 are brackets 24, having slotted apertures 24^a therein, which receive the flattened ends of fulcrum-bars 25, passing through glands 26 in the opposite walls of 20 the frame 10. To prevent these bars 25 from being blown out by the pressure from within, collars 25^a are provided thereon, which lie against the inner sides of the glands 26.

Secured to the projecting ends of the fulcrum-bars 25 are levers 27, which when the door is closed will be in a horizontal position. (See Figs. 3 and 4.) At the outer ends of these levers 27 are balance-weights 28, which lift the door to its seat on the packing 23 and 35 when the pressure is turned on the slots 24^a in the bracket 24 allow the door to move upward and be pressed tightly onto its seat.

To insure that the frame 10 will be equal to all strains to which it may be subjected 40 without danger of bursting, I bridge the front side of the vent above the main door-seat with ribs 10^g, and the rear side is curved outward, as 10^h, which gives the required strength with a minimum of weight.

45 I am aware that prior to this invention steam-boxes and other vessels of this class have been closed by the door being forced forward onto its seat and sealed by internal pressure. Therefore I do not wish to make 50 broad claims to this as a principle, but

What I do claim, and desire to be protected in by Letters Patent, is—

1. In a door of the class described, in combination; a frame 10 secured to the mouth of the vessel to be closed, a passage-way for a 55 door downward through said frame, and a flexible seat arranged around the opening to be closed and designed to receive the rim of the door, hand-levers 12 having devices there-

on for drawing the door to its seat, and balance-levers for raising said door, a flap-door for closing the opening through which the main door slides when being opened, fulcra arranged to support said flap and levers and weights for balancing the same and for bringing it to its seat, substantially as specified. 60

2. In a door and means for closing the same, in combination; a frame 10 secured or integrally fixed to a vessel to be closed, a vertical passage-way for a door through the upper part of the said frame, a rim carrying a packing forming a seat around the opening to be closed, a door arranged to be placed over said seat and levers for raising and lowering the same, and means for drawing said door onto its seat when closed, a flap-door for closing the passage-way hinged or supported on fulcra, said fulcra passing through glands on the opposite sides to the exterior of the frame 10, and levers and balance mechanism fixed on said fulcra, and means for allowing the said door to be pushed tight against its seat by the internal pressure. 70

3. Means for closing a door of the class described consisting of a frame 10 integral with the vessel to be closed, having a vertical passage-way for the door, a closure for said passage-way consisting of a flexible seat 23 arranged around the opening therein, a flap-door made to lie on said seat and supported by fulcra engaging in brackets 24 near opposite ends thereof, and slots in said brackets engaging the flattened ends of the fulcra, whereby the door may be opened or closed, and the internal pressure will be allowed to 80 force it upward and effectively close the aperture, substantially as specified. 85

4. A door for closing a retort or steam-box of the class described, consisting of a dished circular plate having its seating edge turned 90 at right angles to the plane of the seat, means for raising and lowering said door, consisting of a horizontal bar rigidly fixed to a projecting bracket near the lower side of the door, rounded ends of said bar and antifriction- 95 rollers on said rounded ends, in combination with levers fulcrumed at a distance from the door and on a horizontal plane with the center thereof, slotted openings in the forward ends of said levers to receive the antifriction- 100 rollers on the opposite ends of the horizontal bar, and weights on the opposite ends of said levers to counterbalance the door, as specified. 105
